(57) **CLAIM**

The ornamental design for an urban yoke, as shown and described.

DESCRIPTION

FIG. 1 is a front view of an urban yoke showing my new design;

FIG. 2 is a side view thereof;

FIG. 3 is a rear view thereof;

FIG. 4 is a top view thereof;

FIG. 5 is a bottom view thereof;

FIG. 6 is a front elevational view of my design. The material shown in broken lines is for illustrative purposes only and forms no part of the claimed invention; and,

FIG. 7 is a fragmentary side view of the hook portion of FIG.
